AWNING

Neil F. McNeil, Los Angeles, Calif.

Application March 30, 1954, Serial No. 29,773

Term of patent 14 years

(Cl. D21—6)

FIG. 1.

FIG. 2.

To all whom it may concern:

Be it known that I, Neil F. McNeil, a citizen of the United States of America, and residing at Los Angeles, in the county of Los Angeles, State of California, have invented a new, original, and ornamental Design for an Awning, of which the following is a specification, reference being had to the accompanying drawing forming part thereof, in which:

Fig. 1 is a perspective view of an awning, showing my new design; and

Fig. 2 is a side elevational view thereof.

The side of the awning not shown has substantially the same appearance as the side shown in Fig. 2.

Portions of the awning in Fig. 1 are diagonally lined to indicate translucency.

I claim:

The ornamental design for an awning, substantially as shown and described.
